LLOYD G. COPEMAN, OF FLINT, MICHIGAN, ASSIGNOR TO COPEMAN LABORATORIES COMPANY, OF FLINT, MICHIGAN, A CORPORATION OF MICHIGAN.

COOLING UNIT FOR REFRIGERATING APPARATUS.

Application filed June 25, 1926. Serial No. 118,429.

This invention relates to a cooling unit for refrigerating apparatus, and has to do particularly with the provision of a simple, permanent and easily manufactured cooling unit adapted to contain the refrigerating coils and adapted to be positioned in the refrigerating chamber of an automatic refrigerator cabinet.

It is the object of the present invention to provide a refrigerating unit which may be inserted as a complete unit in a suitable refrigerating unit of a cabinet, and which is adapted to contain the refrigerating coils, whereby in operation such a unit is capable of absorbing heat from the interior of the refrigerator, and in turn, cause vaporization of the gas, or liquid in such cooling unit. More specifically, the structure of this novel unit consists of a plurality of refrigerating coils of either the expansion or flooded type which are so arranged, or coiled, as to define one or more sharp freezing chambers and which refrigerating coils are cast embedded in artificial stone. Such artificial stone, when cast, defines the exterior and interior walls of the cooling unit, and also serves as a holdover medium as well as a conducting medium.

A further object of this invention has to do with the manner of forming the walls, and preferably the exterior walls of this cooling unit, and contemplates the casting, or forming, of corrugated walls, the corrugations or serrations of the walls varying in depth and registering with the embedded refrigerating coils which are preferably positioned adjacent the apexes of the corrugations or serrations. By constructing a cooling unit of this type, it is obvious that by providing serrations or corrugations, the effective heat transfer surface of the cooling unit is materially enlarged and that by varying the depth of the corrugations, and by using the same number, or by adding to the refrigerating coils, that I have made it possible to utilize a simple, lightweight cooling unit of relatively small and substantially uniform dimensions for use in refrigerating units of widely varying capacities.

Fig. 1 is a perspective view of a refrigerator cabinet with the front removed and partly cut away to illustrate my novel cool-

ing unit positioned in the refrigerating chamber.

Fig. 2 is a perspective longitudinal and transverse sectional view of my novel cast cooling unit and illustrating the preferred manner of arranging the coils to define the sharp freezing chambers and the manner of embedding the coils in the walls of the cooling unit.

Fig. 3 is a horizontal sectional view taken through one of the sharp freezing chambers of a cooling unit, similar to the unit shown in Fig. 2, and illustrating the manner of casting or providing corrugations or serrations in the outer walls of the unit in order to increase the effective surface area of such unit.

Fig. 4 is a fragmentary sectional view similar to Fig. 3 and illustrating the manner of increasing the capacity of the refrigerating coils as well as increasing the effective surface area of the cooling unit.

Fig. 5 is a detail fragmentary sectional view showing the preferred manner of casting the terminal fixtures for the refrigerating coils cast in the cooling unit.

Fig. 6 is a fragmentary detail sectional view illustrating the preferred manner of casting the well for the thermostatic unit for controlling the flow of refrigerant to the cooling unit.

Fig. 7 is a fragmentary front elevation of the cooling unit illustrating the manner of suspending a cooling unit container within the cooling unit, and also showing the broad surface contact between the container and the grooves for supporting the same.

Hitherto in the forming of cooling units for domestic refrigerators the successful field has been more or less limited to the use of two types of evaporating or cooling units. These types are known as the direct expansion type and the flooded type, and both have their advantages as well as disadvantages. Probably the greater number of domestic refrigerator units utilize the direct expansion principle in combination with what is known as a brine tank. These brine tanks of the prior art have served as holdover mediums to stabilize the refrigerating system and also as more or less efficient means for effecting heat transfer, and also for providing the

necessary sharp freezing chambers. Although these brine tanks have been sufficiently efficient for practical commercial use yet they have all presented the objection of requiring a relatively long time to effect freezing of the ice cubes and the like, and they also have the disadvantage of having soldered or welded joints which always present the liability of leakage.

- 10 The present invention overcomes the difficulties of the known prior art by providing a compact, symmetrical cast cooling unit having the refrigerating coils embedded therein and which is so designed as 15 to meet the heat transfer, or ice melting capacity of domestic refrigerating units of varying size without material difference in general size of the unit. I preferably construct this cooling unit of artificial stone. 20 This is a special form of oxy-chloride cement which I have disclosed in some of my prior applications, and which contains magnesium oxide, a suitable aggregate, such as ground flint, and to which dry mix is added magnesium chloride in solution to make a mix which will either pour, or can be plastically applied as desired. This is simply illustrative of one form of plastic material that may be utilized in effecting my invention and it will 25 be understood that any similar plastic material may be utilized in forming the cast, or plastically formed unit.

This application is a continuation, in part, of my copending applications Serial No. 25 89,519, filed February 20, 1926, and Serial No. 86,719, filed February 8, 1926.

The refrigerator proper may be constructed in any manner desired, and as shown in the drawings, is provided with a refrigerating chamber 1 and suitable food chambers 2 and 3. Adapted to be suitably inserted in the refrigerating chamber 1 is a cooling unit which as shown in Fig. 1, may be generally designated 4. This cooling unit is preferably formed of cast stone as will be presently described, and may be suspended or supported within the refrigerating chamber in any manner desired.

In forming a cooling unit for refrigerators of relatively small capacity, I preferably build or form the coils as illustrated in Fig. 2 to generally define one or more sharp freezing chambers and then cast the cooling unit and the integral sharp freezing chamber, or chambers, so as to form a unit with a smooth exterior as shown in Figs. 1 and 2. This cooling unit may be formed by inserting suitable cores within the outline defined by the coils, inserting the cores and coils in a suitable mould to define the exterior, and then casting the complete unit by pouring the plastic mix of oxy-chloride cement between the cores and the mould walls, and in and around the refrigerating coils. After 45 the plastic stone mix has had sufficient time

to set the cores and mould may be removed in the customary manner.

In the form shown in Fig. 2 the coils 5 are arranged in the form of a figure 8 and as shown, are preferably continuous from the terminal 6 to the terminal 7, and it will be understood that such terminals 6 and 7 may be connected to a suitable expansion valve and condenser unit of any standard apparatus. It will also be understood that the thickness of the walls of my cast refrigerating unit, surrounding the refrigerating coils, may be varied in accordance with the degree of "holdover" desired and in accordance with the ice melting capacity of the particular refrigerator unit.

As is well known in the art, some refrigerating units are designed to embody a large number of sharp freezing chambers, and other refrigerating units vary considerably in what is called refrigerating capacity, or ice melting effect. In order to provide for these units of different size and different capacities, and at the same time to maintain the weight of my cooling unit at a minimum, I preferably provide or cast suitable corrugations, or serrations 8 in the outer walls of the cooling unit. These serrations, or corrugations, are preferably cast on the sides and back of the cooling unit, but it will be understood that they may be formed on all the surfaces of such unit.

As shown in Fig. 3, the corrugations 8 are formed on the exterior walls of the cooling unit, but it will be understood that in case the sharp freezing capacity is desired to be varied that suitable corrugations or serrations may be formed on the interior surfaces of the sharp freezing chambers. These corrugations

whether on the interior or the exterior may be so cast or formed with the plastic stone composition that the parts of the refrigerating coils positioned adjacent the walls of the unit are preferably embedded between the walls forming the corrugations and preferably adjacent the apexes of such serrations or corrugations. It will be understood that these corrugations may be cast

so as to be of any depth desired in order to provide a varying amount of surface area in order to vary the heat transfer capacity of the unit.

If it is desired to increase the refrigerant or evaporating capacity of the refrigerating coils, additional coils may be added, and in Fig. 4 is shown, one method to increase the refrigerant carrying capacity by embedding a series of two refrigerating coils in each corrugation.

It will be understood that refrigerating coils of either the direct expansion type or flooded type may be utilized in forming my novel cast cooling unit, and that in case of the flooded type, that suitable headers may be easily and practically cast embedded as

a part of the cooling unit. It will be further understood that the sharp freezing chambers, which may be designated 9, may be of any size, shape and number desired.

8 In Fig. 5 I have shown the preferred manner of forming the terminal units for the terminals of expansion coils 5 which are particularly adaptable to be used when such coils 5 are utilized with the direct expansion system. The terminal 6, as shown in Fig. 5, may be connected to a suitable expansion valve 11, and which valve 11 may be provided with a suitable housing which may be easily inserted in a suitable well cast in 15 the cooling unit 4. The connection for the other terminal of an expansion coil may be made by means of a suitable member or connection 12 which may also be provided with a suitable housing which is adapted to be 20 received and positioned by a suitable well also cast in the moulded unit 4. As best shown in Fig. 6 the moulded unit 4 is preferably provided with a suitable well 14 for receiving a suitable thermostatic unit 13. 25 This unit 13 may be provided with a thermostatic element 15 adapted to be surrounded by a suitable liquid in the well 14. It will be understood that these terminal connections of the thermostatic unit may be of 30 any contour and of any standard design, the main point being that when the cooling unit is moulded or cast that suitable wells or impressions may be very easily made at any part of the same, whereby the terminal 35 connections or thermostatic unit may be inserted.

A further feature of my invention has to do with the provision of a novel cooling unit, and particularly with the provision of novel guiding and supporting means cast as an integral part of the sharp freezing chamber, or chambers, of the cooling unit, said guiding or supporting means being adapted to receive and suspend the sharp freezing chamber containers in a novel manner. These guiding or supporting means are preferably formed in the nature of grooves in the side walls of the sharp freezing chambers and may be designated 10. These grooves, as shown in Figs. 1, 2 and 7, preferably consist of longitudinally extending depressions which are downwardly tapered, the downwardly tapered portions serving as the guiding and direct supporting means for the containers. The container units may be of any desired form, and in Fig. 7 I have shown a container unit 16 which is adapted for use in freezing ice cubes. The supporting edges of this unit 16 are preferably outwardly flared at 17, and these outwardly flaring portions 17 are preferably of relatively great dimensions. These outwardly flaring portions 17 are adapted to cooperate with the downwardly supporting sides of the grooves 10, and in the preferred form of my inven-

tion the downwardly tapered grooves 10 and the outwardly flaring portions 17 of the containers are so designed as to have a relatively great supporting and contacting surface. The object of this relatively great contact 70 between the container 16 and the supporting walls of the cooling unit is to permit a relatively large amount of conduction and thus cause a relatively large amount of heat abstraction between the interior walls of the 75 sharp freezing chamber and the containers within such chamber. This abstraction of heat from the containers in a relatively large degree by direct conduction, in contrast with the abstraction of the heat by convection, 80 materially reduces the time required for freezing or reduction of temperature of the contents of the containers. The container 16 is provided with suitable partitions 18 for dividing the container into suitable spaces 85 for receiving water or other substance 19 for cooling or freezing the same.

It will thus be obvious that I have provided a cooling unit which may be formed to define suitable sharp freezing chambers 90 whereby the unit is a permanent one and may be directly inserted in the refrigerating chamber of the refrigerator cabinet as a permanent, compact and neat appearing unit. It will furthermore be obvious that by providing a cooling unit formed of artificial stone that such artificial stone not only serves as a good conductor for effecting efficient heat transfer, but also serves as a holdover 95 medium which entirely obviates the use of brine and a brine tank. This combination of a relatively good conductor and a good holdover medium results in a very efficient sharp freezing action in the production of ice cubes, and I have found from experience 100 that by utilizing a cast stone cooling unit that the water within the sharp freezing chamber may be frozen into ice cubes in substantially half the time required to freeze 105 ice cubes in the standard brine tanks now 110 in commercial use.

It will furthermore be obvious that by providing a cooling unit having surfaces which may be readily formed with corrugations of varying depth and area that I have 115 made it possible to form a relatively large number of cooling units of substantially constant size and weight but of widely varied refrigerating capacity.

While my cast stone cooling unit is particularly adaptable and designed in the present illustrated embodiment for use with refrigerating systems of the compression expansion type, it will be understood that my cooling unit is equally well adaptable as a 120 unit in a refrigerating system of the absorption type. It will therefore be understood that I do not intend to limit myself to any specific type of mechanical refrigeration, 125 and that the terms "mechanical" or "auto- 130

- "matic" refrigerating systems apply equally to refrigerating systems of the compression and absorption type.
- What I claim is:
- 5 1. As a new article of manufacture, a cast stone cooling unit for mechanical refrigerating systems having refrigerating coils embedded in the walls thereof and adapted to be inserted as a unit in a refrigerator cabinet.
  - 10 2. As a new article of manufacture, a cooling unit adapted to be inserted in the refrigerating chamber of an automatic refrigerating unit, and comprising a refrigerating coil formed to generally define one or more sharp freezing chambers, and moulded walls surrounding said refrigerating coils to form the exterior walls of the cooling unit and the interior walls of the sharp freezing chamber, or chambers.
  - 15 3. As a new article of manufacture, a cooling unit, for automatic refrigerating units, formed of moulded stone and shaped to define one or more sharp freezing chambers, and a refrigerating coil embedded in the walls of said unit whereby to abstract heat from said sharp freezing chamber, or chambers, and from the refrigerating chamber and food chambers of the refrigerating unit.
  - 20 4. As a new article of manufacture, a moulded cooling unit, a refrigerating coil embedded in the walls of said unit and serrations in one or more walls of said unit to increase the effective heat transfer surface of said unit.
  - 25 5. As a new article of manufacture, a cooling unit for automatic refrigerating systems comprising a separate moulded unit formed to define a sharp freezing chamber, a refrigerating coil embedded in the walls of said unit and surrounding said chamber, or chambers, and serrations formed in one or more walls of said unit to increase the effective heat transfer surface of said unit.
  - 30 6. As a new article of manufacture, a cooling unit for use with refrigerating systems comprising a container having one or more walls defined by a plurality of serrations for increasing the effective ice melting capacity of such surface, or surfaces, and refrigerating coils within said container, and positioned within the wall or walls formed by said serrations.
  - 35 7. As a new article of manufacture, a moulded cooling unit adapted to be inserted within a refrigerating chamber of a refrigerator comprising a refrigerating coil formed to generally define one or more sharp freezing chambers and the exterior surfaces of the cooling unit, and plastically applied walls for embedding said refrigerating coil and for defining the finished interior and exterior surfaces of the cooling unit, one or more of the walls being provided with serrations cooperating with the refrigerating coils to present a relatively large cooling surface.
  - 40 8. A cooling unit adapted to be inserted within a refrigerating chamber of a refrigerator, comprising a moulded unit formed to generally define one or more sharp freezing chambers and the exterior surfaces of the unit, said unit being provided with expansion conduits for receiving a refrigerant for expansion to produce a cooling effect, the walls of said unit being formed of a material acting as a conductor and holdover and being provided with serrations to present a relatively large cooling surface in proportion to the weight and size thereof.
  - 45 9. A cooling unit for use with refrigerating systems comprising a moulded unit formed of cast stone, a wall or walls of said unit being provided with conduits for receiving a refrigerant for expansion, and serrations formed in between some of said conduits of a depth to increase the refrigerating capacity of the unit without materially increasing the weight thereof.
  - 50 10. As a new article of manufacture, a cooling unit for use with refrigerating systems comprising a sharp freezing chamber and downwardly tapered grooves formed in the side walls of the sharp freezing chamber for carrying and suspending the container or containers for such sharp freezing chamber, said container or containers being supported by means of laterally projecting portions which project from the containers and engage the downwardly tapered supporting surfaces of the grooves.
  - 55 11. As a new article of manufacture, a cooling unit for use with refrigerating systems comprising a moulded unit formed to define one or more sharp freezing chambers, refrigerating coils embedded in the walls of said unit and grooves formed in the walls of said chamber or chambers for suspending the container adapted to be inserted in said chamber or chambers.
  - 60 12. As a new article of manufacture, a cooling unit for use with refrigerating systems comprising sharp freezing chamber or chambers, grooves formed in the walls of said chamber or chambers and adapted to receive and suspend suitable containers within the sharp freezing chambers, and permit the containers to extend the entire width of the chamber or chambers, said grooves having supporting surfaces designed to contact with a relatively large area of the suspended container to permit a large degree of direct conduction between the walls of the sharp freezing chamber and container or containers.
  - 65 13. As a new article of manufacture, a cast cooling unit for refrigerating systems provided with expansion conduits in the walls thereof and one or more wells formed in the surface of the unit for the reception

of a suitable connection or connections for the terminals of the expansion coils.

14. As a new article of manufacture, a cast cooling unit provided with expansion conduits in the walls thereof and a well cast in the walls of the unit for receiving a thermostatic unit.

15. A refrigerating apparatus consisting of a casing having a storage chamber therein and a cooling device located adjacent the upper part of said chamber, said cooling device comprising a unit formed of molded stone and a conduit through which a refrigerant is to be circulated, embedded in said stone.

16. As a unit for and in a mechanical refrigerating system of the expansion type, a cooling unit formed of stone and shaped to define one or more sharp freezing chambers, and an expansion coil located in conducting relation with respect to the stone for abstracting heat from the contents of the sharp freezing chamber or chambers by heat conduction through the stone.

17. A refrigerating apparatus consisting of a casing having a storage chamber therein and a separate cooling unit located within the confines of said casing and forming

a link in a mechanical refrigerating system for receiving a refrigerant for expansion, said cooling unit being formed of molded stone, and a conduit through which a volatile refrigerant is to be circulated, located in proximity with the stone to effect heat exchange through the stone by conduction.

18. A cooling unit for mechanical refrigerating systems, comprising a unit formed of stone and shaped to define one or more sharp freezing chambers, said unit being provided with expansion conduits in the walls thereof for receiving the refrigerant for expansion to produce a cooling effect, said stone acting as a conductor and holdover.

19. As a new article of manufacture, a cast stone cooling unit for refrigerating systems provided with expansion conduits formed in the walls thereof and one or more wells formed in the cast stone wall or walls of the unit for the reception of a suitable operating connection or connections forming a part of the refrigerating system.

In testimony whereof I affix my signature.

LLOYD G. COPEMAN.
